UNITED STATES PATENT OFFICE.

MILTON C. NILES, OF OAK PARK, ILLINOIS.

RAIL-JOINT.

SPECIFICATION forming part of Letters Patent No. 432,551, dated July 22, 1890.

Application filed September 19, 1889. Serial No. 324,372. (No model.)

To all whom it may concern:

Be it known that I, MILTON C. NILES, a citizen of the United States, and a resident of Oak Park, in the county of Cook and State of Illinois, have invented certain new and useful Improvements in Rail-Joints, of which the following is a specification.

This invention relates to improvements in rail-joints for uniting the meeting ends of rails, and has for its prime object to dispense with the employment of bolts or other equivalent devices, and to utilize a wedging action as the means for securing the joint to the rails.

Another object is to have the wedge of such a character that it may subserve the double purpose of tightening and securing the joint to the rail and of locking the same in its finally tightened position against accidental dis-

placement.

These objects are attained by the devices illustrated in the accompanying drawings, in which—

Figure 1 represents a side elevation of the meeting ends of a pair of rails, showing a joint applied thereto embodying my invention; Fig. 2, a transverse vertical section thereof on the line 2 2 of Fig. 1; Fig. 3, a top plan view thereof; Fig. 4, a detail perspective view of the binding-plate; Fig. 5, a similar view of the removable wedge-plate, and Fig. 6 a similar view of the wedge.

Similar letters of reference indicate the same parts in the several figures of the drawings.

Referring by letter to the accompanying drawings, A indicates the rail; B, a base-plate provided along one side edge thereof with an upturned overhanging flange C, against and beneath which the flange D of the rail projects, the base-plate at its opposite side being also provided with a longitudinal angular portion E, terminating at the upper edge in an overhanging shoulder F, the whole constituting in effect a hook. Between this hook and the underside of the top of the rail extends a binding-plate G, preferably of slightly-greater length than the base-plate, and provided with depending lugs H at each end thereof, lying at each end of the hook, so as to prevent a

longitudinal movement of the plate in either direction independent of the bed-plate. The lower edge of this binding-plate lies beneath the shoulder F of the hook on the base-plate, as more clearly illustrated in Fig. 2, and is held up tightly against the shoulder and the under side of the head of the rail by means of a wedge I, driven in between said plate and the flange of the rail. In practice this wedge might be opposed by a corresponding incline formed on the under side of the clamping-plate by a suitable thickening thereof at the part J about the center of width thereof; but the opposing incline is preferably provided upon a removable wedging-plate K, fitting into a socket in the thickened portion J, and provided at each end with projecting lugs L, opposing the ends of the plate, so as to prevent longitudinal movement of the wedging-plate independent of the binding-plate.

The inclined face of the wedge I is preferably provided with a longitudinal rib M at the center of width thereof, and the wedge-plate K on its inclined face is provided with a corresponding longitudinal groove N, into which the rib fits and works, so as to prevent the accidental separation of the wedge and wedge-plate by a lateral shifting of the wedge, the wedge-plate being prevented from shifting in turn by its seat within the socket of the binding-plate.

In practice the base-plate is first set in position, the binding-plate then adjusted, and the wedge-plate inserted in position, after which the wedge is driven in from one end thereof until the binding-plate bears tightly against the shoulder F and the under side of the head of the rail, thereby causing the bed-plate to bind with equal force against the bottom of the rails, and thus effect a most rigid joint between the meeting ends of the rails. After the wedge is driven tightly in position, with its smaller end projecting beyond the binding-plate at the opposite end, the end of the wedge may be bent up at substantially a right angle, as illustrated by dotted lines in Fig. 1, and thus serve to effectually lock the wedge in position, and consequently lock all of the parts of the joint rigidly in their tight-

ened positions. Other means, however, may be employed for locking this wedge in position obvious to one skilled in the art, and which are not necessary to be herein illustrated so long as a suitable form of lock for the wedge is employed.

An important feature of my invention is the absence of all bolts and nuts, as a result of which not only is the efficiency of the joint materially promoted, but the cost thereof is materially reduced and the practicability at the same time increased; besides which, the flexure of the binding-plate or any of the other parts of the joint is not depended on for the rigidity of the joint, and the binding-plate is supported and acted upon throughout the length thereof, so that with the parts of suitable thickness the joint is practically indestructible and without the liability to wear of the old forms of joints, in which either the elasticity or spring of the metal or bolts and nuts were depended on for producing the desired rigidity of the joint.

While the wedge-plate K is not absolutely essential to my invention, its use is preferred, because the binding-plate may then be made in straight longitudinal lines and rolled in lengths instead of being forged, as would otherwise be necessary if the incline for the wedge were formed thereon, and thus the expense of the joint is lessened by the employment of this wedge-plate.

This joint is also as readily detachable from the rail as any of the old forms of joints, for it is only necessary to bend down the ends of the wedge or release the other form of lock device employed in connection therewith, when the wedge may be withdrawn and the joint detached from the rail.

To prevent "creeping" of the joint upon the rails, the base-plate may be provided at one side edge thereof with a notch O, in which a spike may be driven when the joint rests upon a tie.

In conclusion, it will be understood that the socket formed in the thickened portion J on the under side of the binding-plate may have any desired configuration, but is preferably concaved, and the top of the wedge or wedge-plate correspondingly convexed or rounded, so as to permit of the wedge adjusting itself to the variations in the angles of the flange upon different rails, and thus adapt the joint for attachment to any form of rail.

Having described my invention, what I claim, and desire to secure by Letters Patent, is—

1. In a rail-joint, the combination, with the rail, of a bed-plate, a binding-plate extending between and bearing against said rail and base-plate, and a wedge fitting between the binding-plate and the flange of the rail, substantially as described.

2. In a rail-joint, the combination, with the rail, of a base-plate, a binding-plate extending between and bearing against said rail and

base-plate, a wedge fitting between said binding-plate and the flange of the rail, and a lock device for said wedge, substantially as described.

3. In a rail-joint, the combination, with the rail, the base-plate, and the binding-plate, of a wedge-plate socketed in the binding-plate, and a wedge fitting between said wedge-plate and the flange of the rail, substantially as described.

4. In a rail-joint, the combination, with the rail and a base-plate provided with a flange at one side edge, against which the flange of the rail bears, and an overhanging hook along the opposite edge thereof, of a binding-plate lying on the under side of and extending between said hook and the rail-top, and a wedge fitting between said binding-plate and the rail-flange, substantially as described.

5. In a rail-joint, the combination, with the rail, of a base-plate provided with an upturned flange, against which the flange of the rail bears, and an overhanging hook at the opposite side edge, and a binding-plate lying beneath and extending from the hook to the under side of the top of the rail, said plate being provided with a socket on the under side thereof, of a wedge-plate fitting within said socket, and a wedge fitting between said wedge-plate and the flange of the rail, substantially as described.

6. In a rail-joint, the combination, with a rail and a base-plate provided with a flange at one side edge, against which the flange of the rail bears, and an overhanging hook along the opposite edge thereof, of a binding-plate lying on the under side of and extending between said hook and the rail-top, and a wedge fitting between said binding-plate and the rail-flange, and a lock device for securing said wedge in position, substantially as described.

7. In a rail-joint, the combination, with the base-plate provided with an upturned flange along one side edge, against which the flange of the rail bears, and an overhanging hook along the opposite edge, a binding-plate lying beneath and extending from said hook to the under side of the rail-top, and lugs on each end of said plate opposing the base-plate, said binding-plate being provided with a socket on the under side thereof, of a wedge-plate fitting in said socket, provided with lugs opposing the ends of the binding-plate, a wedge fitting between said wedge-plate and the flange of the rail, and a lock device for securing said wedge in position, substantially as described.

8. In a rail-joint, the combination, with the rail, of a base-plate, a binding-plate extending between and bearing against said rail and base-plate, and means for causing said binding-plate to impinge against said members, substantially as and for the purpose described.

9. In a rail-joint, the combination, with the

5 rail and a base-plate provided with a flange at one side edge thereof, against which the flange of the rail bears, and an overhanging hook along the opposite edge thereof, of a binding-plate lying on the under side of, bearing against, and extending between said hook and the rail-top, and means interposed be-

tween the binding-plate and the rail for tightening said binding-plate against the hook and the rail-top, substantially as described.
